US00D960464S

(12) **United States Design Patent** (10) Patent No.: **US D960,464 S**
(45) Date of Patent: **** Aug. 9, 2022**

(54) **CHICKEN FEEDER**

(71) Applicant: **Zeyong Zhong**, Jieyang (CN)

(72) Inventor: **Zeyong Zhong**, Jieyang (CN)

(**) Term: **15 Years**

(21) Appl. No.: **29/795,150**

(22) Filed: **Jun. 17, 2021**

(51) LOC (13) Cl. **30-03**

(52) U.S. Cl.

USPC **D30/131; D30/121**

(58) **Field of Classification Search**

USPC .....
